Primary Examiner — Wan Laymon*Assistant Examiner* — Mark Booker*(74) Attorney, Agent, or Firm* — Kevin C. Johnson(57) **CLAIM**

The ornamental design for a razor stand, as shown and described.

DESCRIPTION

FIG. 1 is a perspective view of a razor stand showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view thereof.

The broken lines are directed to the environment and are for illustrative purposes only and form no part of the claimed design.

1 Claim, 6 Drawing Sheets(56)
